UNITED STATES PATENT OFFICE.

DANIEL D. SWEM, OF BRIDGEPORT, CONNECTICUT, ASSIGNOR TO THE ARTISTIC BRONZE COMPANY, OF BRIDGEPORT, CONNECTICUT, A CORPORATION OF CONNECTICUT.

REFRIGERATOR LATCH.

Application filed December 1, 1925. Serial No. 72,468.

This invention relates to latches, especially to a latch for use on refrigerator doors, and has for an object to provide a latch construction involving a vertically reciprocating latch member which may be used on small as well as large latches.

It is also an object of the invention to provide a structure in which the same parts or elements can be used on either right or left hand latches.

It is a further object of the invention to provide a latch in which the strain on the latch and the keeper in the act of slamming the door will be reduced to a minimum.

With the foregoing and other objects in view, I have devised the construction illustrated in the accompanying drawing forming a part of this specification, similar reference characters being employed throughout the various figures to indicate corresponding elements. In this drawing,

Fig. 1 is a front elevation of the latch as applied to a door.

Fig. 2 is an end elevation looking from the right of Fig. 1 and the left of Fig. 3.

Fig. 3 is a rear elevation of the latch.

Fig. 4 is an end elevation looking from the right of Fig. 3.

Fig. 5 is a side elevation of the keeper, and Fig. 6 is a longitudinal section through a latch substantially on line 6-6 of Fig. 3.

The latch comprises a casing 10 which has a flange 11 with screw holes 12 for screws to secure the casing to the door 13. This casing is open on the rear side to facilitate assembly of the latch mechanism, which open side is closed by a plate 14 mounted on the casing by screws threaded into the lugs 15. The latch member comprises a block 16 mounted for vertical reciprocatory movement in the casing. Permanently mounted in the casing is an upright bar 17, preferably a cylindrical bar, which passes through a central opening in the block 16 so that the block may slide on this bar. The inner wall of the casing and the side walls of the block are provided with finished bearing surfaces 18 and 19 respectively, which act as guiding surfaces for the block and also to prevent turning movement of the block on the bar so as to hold it in proper alignment. The surfaces 19 on the other side of the block rub on the inner surface of the plate 14 for the same purpose. The block has a projection 20 extending through the opening 21 in the end of

the casing and carries a roller 22 to engage the keeper 23. The roller is mounted on a stud 24 mounted in the projection 20.

The block is shifted in one direction by a lever 25 pivoted in the casing on the stud 26. This lever is forked at its forward end, the sides 27 of this fork extending on opposite sides of the bar 17 and they are provided with rounded ends 28 projecting into recesses on the opposite sides of the block 16, these recesses providing shoulders 29 on opposite sides of the rounded ends of the lever against which these rounded ends engage to provide an operative connection between the lever and the block. A vertical rod 30 is mounted in the casing to the rear of the block, and the block is provided with a rearward projection 31 having an opening through which this rod extends. A coil spring 32 embraces this rod and reacts at its opposite ends against the upper wall of the casing and the projection 31 of the block so that it tends to hold the block in its lower position. This arrangement provides a guide for the spring so that the spring cannot buckle and gives a smoother and more uniform action because a longer spring can be used, which means less movement for each individual turn of the spring.

The lever 25 has an arm 33 projecting in the opposite direction from its pivot from the fork 27, and an operating handle 34 is pivotally mounted in the casing on the stud 35, this stud extending substantially parallel with the plane of the door so that the free portion or grip of the handle moves toward and from the door about this pivot, and the handle is operated to release the latch by pulling it away from the door in the direction to move the door to the open position. The latch is released by an extension 36 on the handle projecting over and engaging the top of the arm 33 of the lever 25. It will thus be apparent that by pulling outwardly on the handle the extension 36 is depressed, pressing down on the arm 33 and lifting the block 16 with the roller 22 and releasing this roller from the keeper 23, allowing the door to be swung open. The extension 36 which engages the top of the operating lever is beveled off at its opposite sides to provide flattened surfaces 37, so that when the handle is pulled outwardly there will be a rocking action of the arm 33 on the curved surface between these flattened surfaces, and when the lever is in its lowest position the

engagement of the extension 36 with this lever will be the flattened surface 37. Thus at the position where there is the greatest pressure and wear between these two members, that is when the spring is compressed, there is an extended bearing surface between them preventing one surface cutting into the other. As the extension 36 is beveled on both sides the lever may be used for either a right or left hand latch. The latch shown in the drawing is a right hand latch that is used on a door swinging to the right. It is also to be noted that the lever 25 is symmetrical about its longitudinal center line so that it may be used either in a right hand or left hand latch, and the block 16 is also symmetrical for the same reason. The two openings 38 in the rear end of the casing allow use of this casing either for a right hand or left hand latch.

The keeper 23 is so constructed that when the door is closed the latch, through its spring 32, tends to press the door towards closed position and thus hold it tightly closed. For this purpose the keeper is provided with an inclined holding surface 39, and it will be apparent from an inspection of Fig. 5 that pressure of the spring 32 tending to force the latch roller 22 downwardly will cause it to react with this inclined surface to force the roller and the door inwardly, as indicated by the small arrow, to hold the door tightly closed.

The keeper also is provided with an improved striking surface leading to the holding surface 39. This striking surface is in the form of a reverse curve, the outer portion 40 being concave and the inner upper portion 41 being convex. It will be apparent that with this arrangement, as the door is slammed to closed position the roller 22 will first engage the lower outer portion of the concave surface 40, which at the point of first contact is substantially horizontal, so that the roller or latch is given a gradual upward acceleration, the greatest rate of movement being at substantially the central portion of this striking surface or where the concave and convex surfaces join, and then the rate of upward movement gradually decreases until it is substantially zero at the point where the roller drops into engagement with the holding surface 39. It will be obvious that this gradual starting and stopping of the latch movement will greatly decrease the strain on the latch and also the keeper incident to the slamming operation.

The construction described gives a rigid, simple latch which employs the principle of a vertically reciprocating latch, and is so constructed and arranged that this principle may be used on small as well as large latches. This vertical reciprocating latch always moves in a direction normal to the keeper and therefore is always in the same

angular relation to this keeper, which is not true of pivoted latches, which pivoted latches necessarily change their angular position with respect to the keeper. Thus this latch has a more uniform and smoother operation. It is also to be noted that as the end 33 of the operating lever may move downwardly independently of the operating handle, when the door is slammed to closed position there is no movement imparted to the handle and no chance of injury to the operator's hand.

Having thus set forth the nature of my invention, what I claim is:

1. In a refrigerator latch, a casing adapted to be secured to a door, a block mounted for vertical reciprocation in said casing, a spring tending to hold the block in one extreme position, a lever pivoted in the casing and connected to said block, an operating handle pivoted in the casing to swing about an axis parallel with the plane of the door and provided with an extension engaging said lever to swing the same about its pivot, a keeper, and a projection carried by the block to engage said keeper.

2. In a refrigerator latch, a casing adapted to be secured to a door, an upright rod mounted in the casing, a block mounted to reciprocate in the casing and guided by said rod, means to prevent turning of the block on the rod, a spring tending to move the block in one direction, a lever pivoted in the casing to swing in a plane substantially parallel with the door and having a rounded end engaging a shoulder on the block, an operating handle pivoted to swing toward and from the door and having an extension provided with a cam surface to engage said lever, a keeper, and a roller carried by the block to engage said keeper.

3. In a refrigerator latch, a casing adapted to be secured to a door, an upright bar mounted in the casing, a block having an opening through which the bar extends so that the block is guided for vertical reciprocation, said block and casing being provided with bearing surfaces on their opposed faces to prevent rotation of the block on the bar, a lever pivoted in the casing having a forked end engaging shoulders on the block on opposite sides of the bar, a spring tending to move the block in one direction, an operating handle pivoted to the casing to move toward and from the door and having a projection engaging said lever, a keeper, and a roller carried by the block to engage the keeper.

4. In a refrigerator latch, a casing to be secured to a door, a block in said casing, an upright bar extending through the block and mounted in the casing, an upright rod mounted in the casing, said block having an extension through which the rod extends, a spring embracing the rod and reacting at its opposite ends against said extension and the

casing, a lever pivoted in the casing and having a rounded end engaging a shoulder on the block, an operating handle pivoted to the casing to move toward and from the door 5 and having operative connection with said lever, a keeper, and a projection carried by the block to engage said keeper.

5. In a refrigerator latch, a casing adapted to be secured to a door, a keeper, a movable 10 latch mounted in the casing to engage the keeper, a spring tending to move the latch in a direction to engage the keeper, a pivoted

lever for operating the latch, and an operating handle pivoted to the casing provided with a projection to engage the lever to operate the latch against the spring, said projection being beveled at the side to provide a flattened surface arranged to engage the lever at the end of the operative movement 15 to give an increased bearing surface when 20 the spring is compressed.

In testimony whereof I affix my signature.

DANIEL D. SWEM.
